UNITED STATES PATENT OFFICE

101,767

DESIGN FOR A GRAND PIANO

Cyril Farny, St. Charles, Ill., assignor to Wurlitzer
Grand Piano Company, De Kalb, Ill., a corporation of Illinois

Application August 24, 1936, Serial No. 64,545

Term of patent 7 years

To all whom it may concern:

Be it known that I, Cyril Farny, a citizen of the United States, residing in St. Charles, county of Kane, and State of Illinois, have invented a new, original and ornamental design for a Grand Piano, of which the following is a specification, reference being had to the accompanying drawing, forming a part thereof.

In the drawing:

Figure 1 is a perspective view of a grand piano embodiment my new design as viewed from the front.

Figure 2 is a side elevation of the same.

I claim:

The ornamental design for a grand piano substantially as shown.

CYRIL FARNY.
